(57) CLAIM

The ornamental design for a toilet paper holder, as shown and described.

DESCRIPTION

FIG. 1 is a perspective view of a toilet paper holder;

FIG. 2 is a front view therein;

FIG. 3 is a rear view therein;

FIG. 4 is a left side view therein, the right side being a mirror image;

FIG. 5 is a top view therein; and,

FIG. 6 is a bottom view therein.

The broken lines shown in the figures represent portions of the toilet paper holder that form no part of the claimed design.
